[57] CLAIM

The ornamental design for a fluid ejector pump, as
shown and described.

DESCRIPTION

FIG. 1 is an end elevational view of a fluid ejector
pump showing my new design;

FIG. 2 is a side elevational view thereof;

FIG. 3 is an elevational view taken from the end oppo-
site that shown in FIG. 1;

FIG. 4 is an elevational view taken from the side oppo-
site that shown in FIG. 2;

FIG. 5 is a top plan view thereof; and

FIG. 6 is a bottom plan view thereof.
